PRINTING TELEGRAPH APPARATUS

Walter J. Zenner, Des Plaines, Ill., assignor to
Teletype Corporation, Chicago, Ill., a corpora-
tion of Delaware

Application April 18, 1941, Serial No. 389,147

7 Claims. (Cl. 197—73)

The present invention relates to printing telegraph apparatus and more particularly to compensating devices therefor.

The principal object of the invention is to provide a telegraph receiver which is capable of operating reliably and efficiently in any angular position.

Another object of the invention is to provide in a tape telegraph receiver a platen shifting means which automatically compensates for gravitational effects induced by changes in the angular position of the printing device.

Specifically, the arrangement according to the present invention provides for automatically adjusting the tension of the platen shift spring, so that when the printer is so positioned physically as to require the platen shift spring to lift the platen against the force of gravity, the tension or pull of the platen shift spring will be automatically increased to compensate for the increased load imposed thereon. Conversely, when the printer assumes a position so as to cause the platen to shift under the influence of both the platen shift spring and the force of gravity, the tension of said spring is automatically decreased to compensate for the assistance of the gravitational force in moving the platen.

The foregoing and other objects and features of the invention will appear from the following detailed description taken in conjunction with the accompanying drawing, in which,

Fig. 1 is a plan view of the tape printer, with certain parts broken away or removed to show other parts more clearly, showing the compensating device of the present invention;

Fig. 2 is a partial elevational view showing the compensating device of the present invention;

Fig. 3 is a fragmentary perspective view taken substantially on line 3—3 of Fig. 1;

Fig. 4 is a sectional view taken on line 4—4 of Fig. 1; and

Fig. 5 is a fragmentary perspective view taken substantially on line 5—5 of Fig. 1.

Having reference to the drawing in which like reference characters indicate similar parts throughout the several views, the tape printing mechanism to which the compensating device according to the present invention is applied, is of the type disclosed in U. S. Patent No. 1,745,633, issued February 4, 1930 to S. Morton et al. Briefly, the selecting mechanism of the apparatus shown in Fig. 1 comprises a series of primary selectors or swords 12 arranged in superposed relation between spaced guide plates 13, which

are mounted on studs 14 rising from a horizontal plate 16, which is supported in elevated position by a suitable bracket (not shown) rising from the base plate. The circular rear ends of the swords 12 pivotally engage corresponding seats in a series of bell crank levers 17 which are also arranged between the guide plates 13 and are pivoted on a stud 18. The other arms of the bell cranks 17 are provided with pointed ends, and springs 19 are provided to hold the bell cranks and swords 12 in their normal position with the pointed ends of the levers 17 adjacent the periphery of a cam member 20. The cam member 20 is mounted upon the upper end of a shaft 21 driven by a motor 22, and, as it is rotated, a spirally disposed series of cam projections 25 on the cam drum or member 20 are arranged to successively oscillate the levers 17 and reciprocate the swords 12.

In addition to their reciprocating movements, the swords 12 also may swing laterally about their pivotal connections with the levers 17. The pivotal movements of the swords 12 are limited by pins 26 projecting upwardly from the plate 16 and are controlled by the armature of an electromagnet 27. The magnet armature 23 is fixed to a lever 28 pivoted at 29 and limited in its vibratory movement by a pair of adjustable stop screws 30 and 31. A spring 32 connected to the armature lever and to an adjustable front screw 33 tends to hold the armature lever in engagement with the stop screw 31. The free T-shaped end of the armature lever 28 is provided with a pair of spaced depending lugs 35 and 42 which cooperate with pairs of laterally projecting arms 36 and 43 on the swords 12. The lugs 35 and 42 are so spaced that they will align with the contacting end of one or the other of the arms 36 and 43 of each sword 12, according as the controlling magnet 27 is energized or de-energized. In this way, the swords 12 are positioned in either their right-hand or left-hand position as they are reciprocated. The swords act through a series of T-levers 37 to position a set of longitudinally movable notched permutation bars 38. Bars 38 are arcuate in form and are mounted on studs 39 which project upwardly from a fixed segmental plate 40 and extend through short slots 41 in the permutation bars to permit the longitudinal movement of each bar to either one of two positions. The springs 19 normally urge swords 12 to their forward position in engagement with the T-levers 37, and the permutation bars 38 are thereby held in one or the other of said two positions, according to the setting of

the corresponding swords in their right or left-hand position.

Permutation bars 38 correspond in number to the number of selecting intervals of the code combinations or signals. As fully described in the aforementioned patent, the cam drum 20 is permitted to rotate upon receipt of a starting impulse which causes the de-energization of the magnet 27, thereby releasing the armature lever 28 which then responds to the pull of spring 32 to rotate the lever 28 in a clockwise direction. Upon this movement, an eccentric screw 34 cooperates with a plunger 24 which acts in the manner shown in Fig. 5 of U. S. Patent No. 1,884,743 to release, through a lever arrangement, a stop arm (not shown) to initiate rotation of cam 20.

The speed of rotation of selector cam drum 20 is synchronized with the speed of code impulses so that as the armature lever 28 is operated in response to the received impulses, a cam 25 acts upon its associated lever 17 to rock it counterclockwise to bring its sword 12 against the selector lever 28. Swords 12 will be swung clockwise or counterclockwise, depending upon whether abutments 35 and 36 or 42 and 43 cooperate; for example, if abutments 35 and 36 cooperate, then the sword 12 will be swung in a clockwise direction and will assume the position shown in Fig. 1. On the other hand, if abutments 42 and 43 cooperate sword 12 will be swung in a counterclockwise direction to assume the position opposite to that shown in Fig. 1. After the sword 12 has been set in accordance with the nature of the signal impulse and the cam drum 20 has rotated to bring a projection 25 out of cooperative engagement with lever 17, the lever 17 will be actuated in a clockwise direction by its spring 19, carrying its associated sword 12 along with it to impinge the sword 12 against one or the other arm of the T-lever 37, thus rocking the T-lever in a counterclockwise or clockwise direction. Each of the T-levers 37 is pivotally articulated to a code bar 38 so that when a T-lever 37 is actuated in a clockwise or counterclockwise direction, its associated code bar is actuated leftwardly or rightwardly on studs 39. Accordingly, with the mechanism just described, the code bars 38 are set selectively in their rightward or leftward position in response to the impulses of a code signal.

The permutation bars 38 control a set of type bars 44 through the instrumentality of interconnected pull bars 45. As disclosed in the previously mentioned Patent 1,745,633, the pull bars 45 cooperate with aligned notches in the series of code bars, which, when found, permit the pull bar 45 to fall thereinto by means of its actuating spring (not shown) to bring an operating hook thereon into the path of a bail which is vertically reciprocable, as described in said patent. Upon the vertical movement of said bail, the pull bar is raised to cause the type bar 44 associated therewith to be pivoted downwardly to bring the type face thereon into contact with a circular platen 46. The type bar 44 is pivotally mounted in the segment 47 and is pivotally articulated to the pull bar 45 by a rack and pinion arrangement.

The paper tape upon which the characters are printed passes through a guide 48 mounted on a U-shaped bracket 51 and over the roller platen 46, the tape being held in engagement with the platen 46 by a pressure roller 49 that is connected to the platen by gears 52 and 53. A horizontal shaft 54 is rotatably and slidably mounted in front and rear brackets 55 and 56, 75

which project upwardly from the base plate 10, and extends through the arms of the U-shaped bracket 51 and through the roller platen 46. The platen 46 is keyed to the shaft 54 to rotate therewith, suitable feed mechanism (not shown) being provided for rotating the shaft 54 through gears 57 and 58 thereby to rotate the platen 46 and advance the paper tape in a step by step manner.

10 Each of the type bars 44 is provided with two characters, a letters or "lower case" character and by axially shifting the shaft 54, bracket 51 and platen 46, the tape is positioned to receive the impact of either type face of the selected type bars. To guide the shift movement of the platen 46 and hold the bracket 51 against rotation, a horizontal member 59 projects rearwardly from the bracket 56 through an opening in the front arm of bracket 51. Stop collar 61 adjustably mounted on the forward end of the shaft 54 and an adjustable stop screw 62 on the bracket 56 act to limit the shift movement of the platen 46.

The shift movement of platen 46 is effected 25 under the control of special pull bars 63 and 64 which are selectively controlled by the selector mechanism previously described, through the instrumentality of code bars 38. The platen 46 is shown in Figs. 1, 3 and 4 in the latched or "letters" position, wherein printing of lower case characters is effected. When the shift or "figures" pull bar 64 is selected, and is caused to be operated vertically by means of the previously mentioned operating bail (not shown) it operates through its lower horizontally extending portion to rotate a latching lever 65, pivoted on a bracket 66 mounted on base plate 10, to disengage the forward end thereof from a latch 67 secured to the U-shaped bracket 51. The 30 latch lever 65 is normally biased clockwise (as viewed in Fig. 3) by its spring 68. When the platen bracket 51 is thus unlatched, it is urged forwardly by its spring 69, one end of which is fastened to a bracket 71 secured to the bracket 51, and the other end of which is fastened to one 35 end of a lever 72 of the compensating device of the present invention.

When the "letters" or unshift pull bar 63 is selected in the manner shown and described in U. S. Patent 1,745,633 it is operated vertically by the operating bail (not shown). The lower end of the special pull bar 63 is provided with a horizontally extending portion which cooperates with one arm of a lever 73 pivoted on a bracket 74 mounted on the base plate 10. When the pull bar 63 is raised by the main operating bail after a previous unlatching operation by the "figures" pull bar 64, the pull bar 63 acts to rotate lever 73 clockwise (as viewed in Fig. 5) to cause arm 75 of lever 73 to cooperate with arm 76 of a shift rocker 77 (Fig. 4) pivotally mounted at 89 on a bracket 78 supported on base plate 10. Lever 73 is normally biased in a clockwise direction by a light spring 79 to maintain arm 75 thereof in cooperative relation with arm 76 of the rocker 77. To render the relationship between arms 75 and 76 adjustable, the rocker 77 comprises portions 70 and 89 both of which are mounted on pivot 89 and are adjustably related by means of a slot and screw adjustment 90. Portion 73 of rocker 77 is provided with a notch 81 by means of which it is articulated to the extension bracket 71. Thus when the pull bar 63 is raised to rotate lever 73 in a clockwise direction to impart counterclockwise rotation to rocker 77 (Fig. 4) the

platen bracket 51 through the articulation of its extension bracket 71 with notch 81 will be urged inwardly (Fig. 1) or leftwardly (as shown in Fig. 4) against the tension of the platen operating spring 69.

In accordance with the present invention, a mechanism is provided for compensating or adjusting the tension of spring 69 automatically upon changes in physical position of the printing apparatus. This change is effected irrespective of the physical position of the apparatus or change in physical position of the assembly as a whole with respect to gravity. The compensating device of the present invention comprises the above-mentioned lever 72 which is pivotally supported on a bracket 85 mounted on the base plate 10. A counterweight 86 is secured to the left-hand arm of the lever 72, and adjacent the counterweight 86 there is secured to the arm of lever 72 one end of a spring 87 the other end of which is fixed to a spring post 88 mounted in the base plate 10.

Thus, if the apparatus shown in Fig. 1 is considered as being positioned with the shaft 54 disposed vertically, with the bracket 56 lowermost, and with the platen bracket 51 maintained latched by the co-engagement of the lever 65 with locking toe 67, the tension of spring 69 will be automatically reduced by the counterclockwise rocking of lever 72 due to the effect of gravity upon the counterweight 86, moving the counterweight 86 in the direction as exemplified by the dotted line 91 against the tension of spring 87. Then, when the platen bracket 51 is unlatched under the control of the "figures" shift pull bar 64, the platen bracket 51, together with platen 46, will respond to the pull of gravity as well as the reduced tension of spring 69 and fall against the stop 62.

On the other hand, if it is assumed that the apparatus shown in Fig. 1 is positioned in an opposite manner, with its shaft 54 vertical, but with the bracket 55 lowermost, and the bracket 51 latched by the co-engagement of its toe 67 with lever 65, then, when the platen bracket 51 is unlatched under the control of the "figures" shift pull bar 64, the platen bracket 51, together with the platen 46 will respond to the pull of the spring 69 and be drawn against the stop 62. However, under these conditions, the spring 69 will have had its tension increased automatically by the rocking of lever 72 clockwise due to the effect of gravity on the counterweight 86 and the pull of spring 87, moving the counterweight 86 in a direction as exemplified by the dotted line 92. Thus tensioned, the spring 69 will function to raise the platen 46 and bracket 51 up to the stop 62 against the force of gravity.

It is contemplated that the mass of the counterweight 86 and the strength of the springs 69 and 87 are so chosen as to give the most efficient counterbalancing and automatic adjusting effect under existing operating conditions.

Although the present invention has been disclosed in connection with a certain specific embodiment thereof, it is understood that the embodiment shown is given only by way of illustration, and that all forms coming within the

scope of equivalency of the appended claims are intended to be covered herein.

What is claimed is:

1. In a printing device, a platen, driving means for shifting said platen from a first case position to a second case position, power storage means for shifting said platen from said second case position to said first case position, and weighted means effective automatically to vary the power stored in said power storage means whereby said power storage means is effective irrespective of change in physical position of the printing device with respect to gravity without diminishing the effectiveness of said driving means.
2. In a printing device, a movable carriage, spring means for moving said carriage, and gravity-responsive counterbalancing means effective directly on said spring means to vary the power stored therein, whereby the effect of gravity upon said carriage is compensated for automatically irrespective of change in physical position of the printing device with respect to gravity.
3. In a printing device, a movable carriage, spring means for moving said carriage, and gravity-responsive counterbalancing means for automatically varying the tension of said spring means for compensating for the effect of gravity upon said carriage irrespective of change in physical position of the printing device with respect to gravity.
4. In a printing device, a platen, driving means for shifting said platen in one direction, spring means for shifting said platen in an opposite direction, and gravity responsive counterbalancing means effective automatically on said spring means to vary the tension of said spring means whereby said spring means is effective irrespective of change in physical position of the printing device with respect to gravity without diminishing the effectiveness of said driving means.
5. In a printing device, a platen, driving means for shifting said platen in one direction, spring means for shifting said platen in the opposite direction, means for latching said platen against operation by said spring means, and gravity-responsive counterbalancing means effective on said spring means to vary the power stored therein, whereby the effect of gravity upon said platen when unlatched for operation is compensated for automatically irrespective of change in physical position of the printing device with respect to gravity.
6. In a printing device, a platen carriage, spring means for shifting said platen carriage from one position to another, and gravity-responsive means automatically operable to vary the tension of said spring means in response to positional changes of the whole device.
7. In a printing device, a platen carriage, spring means for shifting said platen carriage from one position to another, and gravity-responsive means automatically operable to vary the tension of said spring means in accordance with variations in gravitational effects on said platen due to changes in position of the device as a whole.

WALTER J. ZENNER.
